ATTORNEY.

UNITED STATES PATENT OFFICE.

STEPHEN D. BAKER, OF NEW YORK, N. Y.

PAPER-HOLDER.

Specification of Letters Patent. Patented July 16, 1918.

1,272,598.

Application filed January 20, 1917. Serial No. 143,437.

To all whom it may concern:

Be it known that I, STEPHEN D. BAKER, a citizen of the United States, residing at New York city, in the county of New York and State of New York, have invented certain new and useful Improvements in Paper-Holders, of which the following is a specification.

This invention relates to means for dispensing paper and the like sheet material put up in rolls, and it has for its object to provide a means of this class, suitable for dispensing toilet paper and the like, which will preserve the paper rolled up after the length desired has been torn away and in which the paper roll will be held so that it may be removed (as for replacing it with a full roll when partly exhausted) but preferably only in such a way as to discourage attempts of the casual pilferer to appropriate the paper roll. Another object of my invention is to provide a novel form of wall receptacle, adapted to receive the moving parts of the dispensing means or for other substantially kindred purposes.

In the accompanying drawing, Figure 1 is a front elevation of the device;

Fig. 2 is a side elevation, showing the device in place in a wall, which appears in section, a part of the receptacle of the device being broken away;

Fig. 3 shows the moving parts in plan and the two sides of the receptacle in horizontal section;

Fig. 4 is a longitudinal sectional view of the roller on which the roll of sheet material is wound, its interior mechanism appearing in elevation;

Fig. 5 is a view similar to Fig. 4, but showing said mechanism with the trunnions retracted; and,

Fig. 6 is an end view of the roller.

I provide a receptacle having two sides *a*, and a wall *b* which in the preferred form is concavo-convex and forms the top, back and bottom of the receptacle; the receptacle also preferably includes a projection *c* at the front, such projection being a curved extension of the wall *b*, and brackets *d* for said projection which are extensions of the sides *a*, *d* and *c* forming a hood at the front of the receptacle, which is otherwise open from

top to bottom. The receptacle may be composed of some ceramic material, as glazed china, thus being adapted to harmonize with the tiled wall of the modern bath-room, into which it is set in the manner shown in Fig. 2. The hood *c* *d* protects the roll of paper and the interior of the receptacle from dust and spatterings of water. The side walls *a* have near the front edges thereof openings *e*, one of which may be non-circular (Fig. 2).

f is a cylindrical roller on which the roll of paper *g* is adapted to be placed. It has a ferrule *h* at each end, and these are provided with spurs *i* to prevent the roll from slipping rotatively on the roller. Extending axially through the roller is the means on which it is journaled and which includes the trunnions *j* and *k* to be received in the openings *e*, one of them being non-circular and fitting the non-circular opening. The trunnions *j* *k* are retractive, and to this end the said means preferably includes three main members linked together, the intermediate member *l* being in the present instance a link pivoted on a transverse pin *m* in the roller.

Describing the member which includes the trunnion *h*: *n* and *o* are two aligned bushings affording bearings for the roller *f*, being arranged in its axial bore *f'*, said bushings having reduced projections *n'* projecting toward each other and the bushing *n* having the trunnion *k* as an integral part thereof. The bushings *n* and *o* are swiveled on an axial pin *p* upset to form a head at each end thereof as shown. *q* is a torsion spring receiving the projections *n'* *o'* of the bushings and having its ends fixed in the latter. Bushing *o* is provided with an inward angular lug *n''* which is penetrated by the pin *p*. There is a clevis *r* pivotally connecting one end of link *l* with the inner end of the member now being described, to wit, by said clevis having its outer end bent off and penetrated by the pin *p*, standing between the bushing *o* and its lug *n''* and capable of universal movement with respect to the pin.

The member which includes the trunnion *j* may be thus described: There is a bushing *s* also arranged in the bore *f'* of the roller and affording a bearing for the roller, the same having the trunnion *j* as an inte-

gral part thereof. It is pivotally connected with the end of link *l*, opposite to that to which clevis *r* is attached, by the clevis *t*. This clevis has a longitudinal slot *t'* receiving 5 a transverse pin *u* set in the roller, and between the pin and the bushing *s* is interposed a spring *v*. The bore *f'* is enlarged, as at *f''*, to permit the articulation of the link *l*, and at one side an opening *f'''* may be provided to permit access to the bore, as in assembling the parts.

The pivot between the clevis *t* and the link *l* is preferably formed by the bent off end *w* of a push rod *x* which slides in a bore *y* extending to and opening at the end face of the roller near its periphery. As shown in Fig. 2, only a small segment of the roller is exposed by the adjoining side wall *a* of the receptacle when the roller is mounted therein, 15 and the bore *y* is so disposed that it is covered by said wall unless the roller is turned so as to bring it within said segment. Thus, and because it is small, it is practically concealed to the casual observer.

25 Operation: A roll of paper being slipped onto the roller, and the trunnions *j k* pressed in against the tension of the spring *v*, the roller is introduced into the receptacle until the trunnions oppose the openings *e* and 30 spring outward into them. The trunnions being inaccessible at their ends, because the receptacle is set in the wall, the roller cannot be removed from the receptacle, as in the attempt to appropriate the paper roll, 35 until all the paper has been unwound therefrom in the regular way, except the operator knows the key to its removal; that is, under these conditions the paper roll cannot be removed (as, for instance, to substitute 40 for it a fresh roll when it has become more or less depleted) unless a nail *z* or the like (Fig. 3) be applied at the bore *y* against the end of the push-rod *x* and made to force the link *l* from the position shown in Fig. 45 4 to that shown in Fig. 5, thus retracting the trunnions, and this of course can only be accomplished when said bore is exposed as in Fig. 2.

The trunnion *k* being held against rotation in the receptacle, when the end of the paper is drawn upon the spring *q* is put under tension, it being fixed at one end to the bushing *n* and at the other to the bushing *o* which has at best but limited rotary 55 movement with reference to the clevis *r*, which in turn is held against rotating in the roller by the link *l* and its pin *m*. Therefore, as soon as the length of paper unrolled is torn off and the roller thus released, the roller is rotated backward by the spring to wind up so much of the paper as might otherwise be left free.

I do not wish to be limited to any of the details herein set forth, what I claim being:

65 1. In combination, a support having

spaced supporting portions, a revolute roller on which to place a roll of sheet material arranged between said portions and having all but a relatively small part of its surface at one end thereof covered by the 70 corresponding supporting portion, means affording an axial journal for and torsional resistance to the rotation of the roller and including trunnions respectively arranged in said portions, one of said trunnions being 75 retractive and one being non-revolute, and means, exposed at one end of said roller and near its periphery, for imparting reTRACTING movement to the retractive trunnion.

2. In combination, a support having spaced supporting portions, a revolute roller on which to place a roll of sheet material arranged between said portions and having all but a relatively small part of its 80 surface at one end thereof covered by the corresponding supporting portion, means affording an axial journal for the roller and including trunnions respectively arranged in said portions, one of said trunnions being 85 retractive, and means, exposed at one end of said roller, and near its periphery, for imparting reTRACTING movement to the retractive trunnion.

3. In combination, a support having 90 spaced supporting portions, a revolute roller, arranged between said portions, on which to place a roll of sheet material, and a system of parts affording an axial journal 95 for and torsional resistance to the rotation of the roller and including retractive trunnions arranged respectively in said supporting portions, one non-revolubly, and also including means, connecting said trunnions, to cause conjoint reTRACTING movement 100 thereof.

4. In combination, a support having spaced supporting portions, a revolute roller, arranged between said portions, on which to place a roll of sheet material, a 110 system of parts affording an axial journal for and torsional resistance to the rotation of the roller and including conjointly reTRACTING trunnion-affording members arranged respectively in said supporting portions, one non-revolubly, and a link pivotally connecting the adjoining ends of said 115 members.

5. In combination, a support having spaced supporting portions, a revolute 120 roller, arranged between said portions, on which to place a roll of sheet material, a system of parts affording an axial journal for and torsional resistance to the rotation of the roller and including conjointly reTRACTING trunnions arranged respectively in 125 said supporting portions, one non-revolubly, and means, exposed at one end of the roller, for imparting reTRACTING movement to the trunnions.

6. In combination, a wall receptacle adapted to be built into a wall with its front substantially flush with one face of the wall and formed of an integral piece of material with a back and two sides and being open at the front, and means to support revolubly a roll of sheet material in said receptacle with

its axis horizontal and the roll projecting at the front, said receptacle also having an integral hood projecting from the front thereof above said opening and adapted to cover the projecting part of said roll.

In testimony whereof I affix my signature.

STEPHEN D. BAKER.
